UNITED STATES PATENT OFFICE

FRANK BERTRAM, OF ROSLINDALE, MASSACHUSETTS

FIREPLACE SCREEN

Application filed April 2, 1931. Serial No. 527,205.

This invention relates to improvements in screens for fire-places or the like, and has for its principal object the provision of a screen panel which is simple and economical to manufacture and in which the vertical and horizontal members of the screen frame are rigidly interconnected at the four corners thereof by a braced joint of improved construction, and in which the horizontal frame members consist of channeled sheet metal strips adapted to receive and to be clamped upon the screen margin.

Further objects of the invention reside in the structural features hereinafter described in connection with the accompanying drawings illustrating a recommended embodiment thereof. It will be understood however that the specific details of the illustrated screen may be varied to suit particular purposes without departing from the essence of this invention as defined in the appended claims. In the drawings,

Fig. 1 is a front view of a fire screen constructed in accordance with the invention;

Fig. 2 is a fragmentary elevation, partly in section of a corner of one of the screen panels shown in Fig. 1;

Fig. 3 is a section taken on line 3—3 of Fig. 2;

Fig. 4 is a plan view of the horizontal frame member of Fig. 2;

Fig. 5 is a bottom view thereof;

Fig. 6 is a detail of the vertical frame member of Fig. 2;

Fig. 7 is a section on line 7—7 of Fig. 4; and

Fig. 8 is a similar view showing the mode of clamping the wire screening within the horizontal, channel member.

In the particular embodiment chosen for the purpose of illustration in Fig. 1, the fire screen comprises three sections or panels of similar construction, each panel comprising a rectangular frame having horizontal members 9 of the identical form, and vertical members 10, the frame being rigidly connected at the corners of the panel, and a strip of wire cloth or screening 11 of suitable mesh for the purpose desired, having its margins attached to the respective frame members.

As illustrated more clearly in the typical panel corner of Fig. 2, the horizontal frames 9 are channeled or substantially U-shaped in cross-section and are provided at their opposite ends with projecting ears 12 having apertures 13 therethrough. The sides 14 of the channel have inwardly directed bottom flanges 15 which are preferably offset with respect to each other (Figs. 7 and 8) and which constitute opposed jaws for clamping the margin of the screening within the upper and lower members 9.

The vertical frame rods or bars 10 have reduced ends or tips 16 providing annular shoulders 17, and the tips 16 are received in and preferably project through the apertures 13 at the ends of the horizontal members 9 with the shoulders 17 seating against the under face of the ears 12, and the sides 14 embracing the rod and preferably fixed thereto by spot welding as indicated at 18. The sides of the screening 11 may be attached to the vertical rods by helical wires 19 which encircle the respective rods and are threaded through the margins of the screening. When two or more panels are employed, adjacent panels may be pivotally connected by links 20 fastened to the projecting ends of complementary rods 10.

In order to provide a firm brace for the rods at the corner joint, the bottom flanges 15 are cut away at their opposite ends as best shown at 21 (Fig. 5) so that the flange ends are inwardly offset from the apertures 13. Thus, when the rod end 16 is inserted in said apertures, the side of the rod abuts the ends 21 of the flanges and provides a perfectly square joint which is rigidly secured by the welding 18 or other fastening means. Any tendency that the frame may become bent or twisted out of shape is thereby obviated, and the screening is held taut at all times.

The panel elements may be readily assembled before securing the corner joint, and it will be understood that the upper and lower ends of the screening are pinched or clamped between the flanges or jaws 15 by bending the channel sides 14 inwardly from the position of Fig. 7 to that of Fig. 8. The offset rela-

tion of the flanges ensures a tight grip, irrespective of the particular character of the screening, and such offset may be easily provided by making one of the channel sides deeper than the other. The top and bottom channel frames may be stamped and shaped from a sheet metal blank by simple operations, and the entire panel is easy and inexpensive to manufacture, durable in use and 10 attractive in appearance without sacrifice of operative efficiency.

A screen panel thus constructed may be employed for a variety of purposes, and I do not intend to restrict the use of my invention to the particular type of fire-screen here- 15 in illustrated.

I claim:

1. A screen panel comprising a rectangular frame having opposite channel shaped 20 members and rod-like members connected to the ends of the respective channel members, at the corners of the frame, the sides of each channel member having inwardly directed bottom flanges offset with respect to each 25 other for clamping opposite ends of the panel screening therebetween.

2. A screen panel comprising a rectangular frame having opposite channel shaped members and rod-like members connected to 30 the ends of the respective channel members, at the corners of the frame, the rod member having reduced ends and the channel members having apertures receiving said ends, and the sides of the channel members embracing 35 the rod members and being secured thereto.

3. A screen panel comprising a rectangular frame having opposite channel shaped members and rod-like members connected to the 40 ends of the respective channel members, at the corners of the frame, the rod members having reduced ends and the channel members having apertures receiving said ends, and the ends of the bottom flanges abutting the sides 45 of the respective rod members thereby to brace the frame at the panel corners.

4. A screen panel comprising a rectangular frame having opposite channel shaped members and rod-like members connected to 50 the ends of the respective channel members, at the corners of the frame, wire screening enclosed by said frame, the ends of the screening being clamped within the respective channel members, and means encircling the rod 55 members and engaging the sides of the screening for securing said sides thereto.

5. A screen panel comprising a rectangular frame having top and bottom members formed of sheet metal bent into channel 60 shape, and having apertures at their opposite ends, side bars having reduced ends received in the apertures of the respective channel members, and wire screening enclosed by said frame, the sides of the channel members having 65 inwardly bent flanges transversely offset

with respect to each other and adapted to be pinched together by bending said sides toward each other for clamping the margins of the screen therebetween.

6. A screen panel comprising a rectangular frame having top and bottom members formed of sheet metal bent into channel shape, and having apertures at their opposite ends, side bars having reduced ends received in the apertures of the respective channel members, and wire screening enclosed by said frame, the sides of the channel members having inwardly bent flanges transversely offset with respect to each other and adapted to be pinched together by bending said sides toward each other for clamping the margins of the screen therebetween, said sides extending outwardly beyond the ends of said flanges and embracing opposite sides of the respective bars, and the flange ends abutting edgewise against the inner sides of said bars. 70 75 80 85

7. A screen panel comprising a rectangular frame having opposite channel shaped members and rod-like members connected to the ends of the respective channel members, at 90 the corners of the frame, the sides of each channel member having inwardly directed bottom flanges for clamping opposite ends of the panel screening therebetween.

8. A screen panel comprising a rectangular frame having top and bottom members formed of sheet metal bent into channel shape, and having apertures at their opposite ends, side bars having reduced ends received in the apertures of the respective channel members, and wire screening enclosed by said frame, the sides of the channel members having inwardly bent flanges adapted to be pinched together by bending said sides toward each other for clamping the margins of the screen therebetween. 95 100 105 110 115

9. A screen panel comprising a rectangular frame having top and bottom members formed of sheet metal bent into channel shape, and having apertures at their opposite ends, side bars having reduced ends received in the apertures of the respective channel members, and wire screening enclosed by said frame, the sides of the channel members having inwardly bent flanges adapted to be pinched together by bending said sides toward each other for clamping the margins of the screen therebetween, said sides extending outwardly beyond the ends of said flanges and embracing opposite sides of the respective bars, and the flange ends abutting edgewise against the inner sides of said bars. 115 120 125

In testimony whereof I affix my signature.

FRANK BERTRAM.
